UNITED STATES PATENT OFFICE

GERTRUDE B. MENDELSON, OF PAINESDALE, MICHIGAN

DESIGN FOR A WALL RACK OR SIMILAR ARTICLE

Application filed August 11, 1931. Serial No. 40,821. Term of patent 7 years.

To all whom it may concern:

Be it known that I, GERTRUDE B. MENDELSON, a citizen of the United States, residing at Painesdale, in the county of Houghton and State of Michigan, have invented a new and useful, original, and ornamental Design for a Wall Rack or Similar Article, of which the following is a specification, reference being had to the accompanying drawings, forming part thereof.

I claim:

The ornamental design for a wall rack or similar article, as shown.

GERTRUDE B. MENDELSON.
